REFRACTORY AND HEAT INSULATED
INDUCTION HEATING HEAD

Meredith P. Albertson, Jr., Detroit, Mich., assignor, by mesne assignments, to The Ohio Crankshaft Company, Cleveland, Ohio, a corporation of Ohio

Application July 8, 1946, Serial No. 681,793

3 Claims. (Cl. 219—13)

1

This invention relates to heating heads as employed primarily for internal tube heating by electrical induction.

In the copending application of Harold A. Strickland, Jr., Serial No. 572,461 (now Patent No. 2,457,845, dated January 4, 1949), there is described an induction heating apparatus applicable to the heating of the internal bores of workpieces, such as rifles and the like, wherein the diameter of the bore gives rise to considerable difficulty in obtaining adequate heat in the bore surface. An induction heating head is used in this prior application comprising a heating coil formed of a hollow conductor and possessing a core of ferromagnetic material to increase the heating capacity of the unit. This coil is enclosed in an external insulating layer and is adapted to be moved in juxtaposition to but out of contact with the internal surface of the workpiece. By this means heat is developed in the workpiece surface. A difficulty in this former construction resides in the fact that in some uses due to radiation and conduction from the heated surfaces of the workpiece, both the coil and a powdered iron or other ferromagnetic core material are subject to such high temperatures as to modify the coil or core structure disadvantageously.

Primarily, therefore, one of the objects of the invention is to provide an induction heating head of such structure as to prevent overheating of the coil and core. Another object is to provide a head structure which will tend to prevent arcing from the head to the workpiece. An additional object is to provide an induction heating head which tends to resist twisting when passed in heating relationship to a workpiece, this effect being due to the magnetic interaction of the adjoining surfaces and frequently resulting in breaking of the coil connections.

A more specific object of the invention is the provision of an induction heating head adapted to lie adjacent to but spaced from the inner surface of an enclosing workpiece, the head comprising a coil formed of an electrical conductor; a ferro-magnetic core within the coil; a casing enclosing the side at one end of the coil; a refractory electrically nonconductive filler embedding the coil conductor and spacing the coil from the casing and a refractory surface material on the outside of the casing and the exposed end of the coil.

Still another specific object of the invention is an induction heating head comprising a coil formed from an electrical conductor; a ferro-

2

magnetic core within the coil; an inflexible casing enclosing the side and one end of the coil; a layer of electrical strip insulation lining the inside of the casing and a granular filler embedding the coil conductor and spacing the coil from the casing and insulation layers.

Other objects of the invention pertain to the various details of construction as will appear on consideration of the following disclosure of a form of the invention which may be preferred.

In the accompanying drawings:

Figure 1 is a longitudinal section through the induction heating head, the support means for the head, and the associated workpiece; and

15 Figure 2 is a section taken along lines 2—2 of Figure 1 illustrating the construction of the coil and core elements of the head.

In Figure 1 the workpiece 1, which may be a rifle tube or other workpiece, is shown as vertically positioned with attachment means (not shown) at the upper end thereof for transmission of rotational and axial movement in progressive heat treatment. Adapted for positioning within a workpiece is a heating coil unit, generally indicated by the numeral 5, composed of a coil 6, a core 7 therein, a filler 8 surrounding the coil, an insulating casing 9 surrounding the filler, a protective cup 10, and a layer 11 of ceramic cement or other material surfacing the cup 10 externally. 20 The coil 6 is preferably of copper conductor tubing in order to secure low electrical resistance and high heat conductivity. The core is preferably of powdered iron as affording the most satisfactory ferro-magnetic properties, although other types of cores, such as laminated sheet steel and the like, may be used. The insulating casing 9 may consist of glass tape, glass string, mica or similar substance possessing high electrical insulation and dielectric characteristics. It is formed in a plurality of layers around the side and base of the coil enclosing the filler material 8 which may be of any suitable ceramic or cement, for example, water or sauereisen cements. 25 This cement embeds the coil turns and has a substantial thickness as shown in the drawing relative to the diameter of the coil conductors. This filler material should resist the high temperatures and possess high electrical resistivity and a low coefficient for heat expansion.

The protector cup 10 is also of insulation material which possesses high dielectric and electrical resistivity characteristics. Also, it should be refractory in nature with a low heat coefficient for expansion, and should have the capability of

resistance to the modifying effects of oil and water employed in the quench system. Suitable materials for this cup consist in glass, quartz, asbestos cement, steatite, sillimanite, or soap stone. The surfacing material for the cup may be the same as the filler material 8.

The head unit 5 as above described is supported within the tubular space of the workpiece by means of the coil terminals 12 and 13, the terminal 12 extending upwardly from the coil at one side thereof in extension of the top turn 14 of the coil, whereas the terminal 13 connects with the lower turn 15 of the coil by means of a central coil section 16 passing upwardly through the coil and core to the terminal 13.

The guide ring 20 for the heating head is placed directly above the head unit 5 and consists of a cylindrical metal block having two vertically extending apertures, aperture 21 being relatively large and slightly off center, whereas aperture 22 is relatively small corresponding with the dimensions of the coil terminal 12 and is positioned adjacent the ring edge directly in line with the terminal 12. Through the central opening 21 the terminal 13 extends into connection with a connecting tube 23 which in turn makes connection through the conical coupling 24 to the inner lead-in conductor 25 of the electrical circuit. This conductor is in the form of a shell having a relatively large interior space for the supply of coolant and is adapted to extend axially through the bore of the workpiece to the bus bar connections at the top of the apparatus. An insulation tube 30 is fitted snugly within the guide ring aperture 21 to extend substantially above and below the ring. This tube encloses the coil terminal 13 and insulates electrically this terminal as well as prevents leakage of coolant from chamber 28.

Surrounding the inner conductor 25 is a casing 26 of insulation material, preferably a refractory substance, which extends also over the coupling 24 and connecting tube 23. Surrounding the insulation casing and displaced therefrom is a metal tube 27 forming a shell of lesser thickness than that of the shell 25 and constituting the outer conductor of the electric circuit. Connection is made to the coil terminal 12 by fixed engagement of the end of the shell 27 with the guide ring 20, as shown in Figure 1 of the drawings. As clearly appears from this figure, the outer conductor is adapted to fit relatively closely within the workpiece bore, and since the thickness of the shell is relatively small, there is a degree of flexibility in this conductor which permits adjustment of the same relative to the workpiece. This is of considerable importance in bores of substantial length and facilitates the utilization of the head for heating of exceptionally small bores.

The space between the insulation casing 26 and the outer conductor 27 is such as to permit the passage of coolant down to the space 28 formed between the ring and the contracted end 29 of the insulation. Thence the coolant may pass into the coil through the lead-in terminal 12 and outwardly through the terminal 13 and connector 23 into the interior space of the inner conductor 25.

By the arrangement as above described it appears that the induction heating coil 6 is spaced from the surface of the workpiece bore by a layer of filler material, such as ceramic or cement, layers of insulating material such as glass tape or mica, a rigid protector cup, such as quartz, and

an external insulating layer around the cup so that any tendency for an electrical discharge or arc to form between the coil turns and the workpiece is removed. Thus pitting of the copper of the coil with resultant deterioration, as well as inefficiency in the actual heating operation, is reduced or prevented. It is pointed out further that the flow-back of heat from the workpiece to the coil and the associated core is greatly reduced by the presence of the intervening filler compound and the miscellaneous layers of insulating material having low heat conductivity. Maintenance of the coil temperature at a substantially uniform value insures uniformity in the current flow and, in conjunction with the absence of arcing, maintains the timing constants at a uniform value, thus preventing any change in the over-all heating characteristics of the apparatus. Noteworthy also is the rigidity of the structure in that the filler encasing enclosures, in conjunction with the protecting cup 10, prevents twisting action on the coil as it moves into heating relation with the workpiece, so that breakage of the coil lead-in connections or terminals 12 or 13 is prevented.

Modifications of the structure in adaptation thereof for varied uses may be made and hence no limitation is implied by the specific showing other than may be required by the claims hereto appended.

What is claimed is:

1. An induction heating head adapted to lie adjacent but spaced from the inner surface of an enclosing workpiece comprising a coil formed of an electrical conductor, a ferro-magnetic core within said coil, a casing enclosing the side and one end of said coil, a refractory electrically non-conductive filler embedding the coil conductor and spacing the coil from the casing, and a refractory surfacing material on the outside of said casing and the exposed end of said coil.

2. An induction heating head comprising a coil formed from an electrical conductor, a ferro-magnetic core within said coil, an inflexible casing enclosing the side and one end of said coil, a layer of electrical strip insulation lining the inner side of said casing, and a granular filler embedding the coil conductor and spacing the coil from the casing and insulation layers, said filler being refractory and possessing high electrical resistivity and a low coefficient of expansion for heat.

3. An induction heating head comprising an electric coil, a ferro-magnetic core within said coil, an inflexible casing enclosing said coil, a layer of glass tape on the inside of said casing, and a cementitious filler embedding said coil and spacing the glass tape layer from the coil.
